(57) **CLAIM**

The ornamental design for a case for a mobile phone with detachable tripod mount, as shown and described.

DESCRIPTION

FIG. 1 is an isometric view of the case of the present design, defining top, bottom, left and right sides for drawings 2-7. FIG. 2 is an isometric view of the present design shown with mounting clips installed.

FIG. 3 is an isometric view of the front side of the present design.

FIG. 4 is a back view of the present design with mounting clips installed.

FIG. 5 is a front view of the present design with mounting clips installed.

FIG. 6 is a top view of the present design.

FIG. 7 is a bottom view of the present design.

FIG. 8 is a left view of the present design.

FIG. 9 is a right view of the present design; and,

FIG. 10 is an isometric view of the present design shown mounted to a handheld monopod for reference.

The broken line showing of the inserted phone, mounting clips, logo and monopod throughout the figures illustrates environment and forms no part of the claimed design.

The xshot™ logo depicted in broken lines throughout the figures is a registered trademark of XSHOT LLC.
